ATTORNEYS.

UNITED STATES PATENT OFFICE.

JOHANN G. KEES, OF NEBRASKA CITY, NEBRASKA.

DESIGN FOR A CORN-HUSKER PAD.

SPECIFICATION forming part of Design No. 30,337, dated March 14, 1899.

Application filed February 9, 1899. Serial No. 705,122. Term of patent 14 years.

To all whom it may concern:

Be it known that I, JOHANN G. KEES, a citizen of the United States, residing at Nebraska City, in the county of Otoe and State of Nebraska, have invented and produced a new and original Design for a Corn-Husker Pad, of which the following is a specification, reference being had to the accompanying drawing, forming a part thereof, which represents my pad in plan view.

One side of the pad forms an obtuse angle

and the other is concave. Each end is provided with a V-shape notch *a*, and one of said ends has two slits *b*, which are located at one side of the notch therein.

15

What I claim is—

The design for a corn-husker pad as shown and described.

JOHANN G. KEES.
